JOB A. DAVIS, OF WATERTOWN, NEW YORK.

Letters Patent No. 86,372, dated February 2, 1869.

IMPROVEMENT IN AUTOMATIC FEED-WATER DEVICE FOR BOILERS.

The Schedule referred to in these Letters Patent and making part of the same.

To all whom it may concern:

Be it known that I, JOB A. DAVIS, of Watertown, in the State of New York, have invented certain Improvements in Mechanism for Feeding Water to Steam-Boilers; and I do hereby declare that the following, taken in connection with the drawings which accompany and form part of this specification, is a description of my invention, sufficient to enable those skilled in the art to practise it.

My invention has for its object the feeding or supplying of water to boilers by a self-acting apparatus, of such a character, and having such a mode of operation; that the mere weight of the water required for feeding shall of itself actuate it, and that it shall need no independent power or engine with pumps to force the water into the boiler; and to this end,

It consists in a novel construction and arrangement of a reservoir, (having, as may be desired, either one or two water-chambers,) arranged to swing upon the supply-pipe, so that the water flowing into the chamber shall cause the reservoir to descend, and in so doing open the water-passage from it to the boiler, and a steam-passage from the boiler to the chamber, to equalize the pressure.

It consists, further, in a provision for adjusting the extent of downward movement of the tank or reservoir, to graduate the rapidity of supply of water to the boiler; in a provision for adjusting the period of descent of the tank, in order to graduate, at will, the quantity of water desired for a single injection; and in certain details of construction hereinafter specified.

The accompanying drawings illustrate an apparatus for practising my invention, of which—

Figure 1 is a vertical section through line 1-1 of fig. 2;

Figure 2 is a vertical section through line 2-2 of fig. 1;

Figure 3 is a vertical section through line 3-3 of fig. 1; and

Figure 4 is a vertical section through line 4-4 of fig. 1.

Similar letters indicate similar parts in the different figures.

A is a vertical boiler, of any known form of construction, my improvements being shown as applied thereto.

B is a tube or conveyer, through which the water, from any ordinary penstock, reservoir, or other source of supply, is conducted to and through my apparatus, and thence to the boiler.

C is a plug, fitting snugly and arresting the passage of water through the tube, for a purpose hereinafter stated.

D is a diaphragm, preferably forming part of the plug C, and serving to divide that portion of the tube B between the outer casing of the boiler and the solid plug C, into two separate compartments.

E is a water-conveying tube, for conducting water

from that compartment of the supply-tube which lies beneath the partition or diaphragm D, and thus supplying the boiler, whilst F is a similar but shorter tube or pipe, for the passage of steam from the boiler to the compartment lying above the partition D, and thence into the tank or reservoir G, for a purpose and in a manner hereinafter more fully described.

This tank is preferably formed substantially as shown in the drawings, having two compartments, separated by a central partition, H.

It is also provided with a tube or sleeve, I, of such size as to admit of placing the reservoir upon the tube, and permit the same to rock thereon.

K is a spiral spring upon the tube B, and serving, by means of nut L, to allow of giving any required degree of pressure against the reservoir, whose other side abuts against a shoulder, M, on tube B, this pressure regulating the facility with which the reservoir G may rock upon its support.

N are pipes, serving to convey the inflowing water from supply-tube B through a small orifice, (one or more, as may be desired,) marked 1, to the chambers 2, 3, alternately of the reservoir G, the particular one of these chambers which shall for the time being receive the water being determined by the position of the reservoir; fig. 2 showing the reservoir in two positions, one indicated by black and the other by red lines, the former allowing the water to pass from B, through orifice 1 and pipe N, to chamber 2, and the latter allowing it to pass through the same orifice and pipe N', to chamber 3.

O are similar pipes on the opposite side of reservoir G, to admit steam at proper periods, alternately, into the chambers 2, 3, of the reservoir; these pipes O communicating, by means of proper orifices, 4, 5, with the chamber above diaphragm D, and thus with the steam-pipe F. (See figs. 1 and 3.)

Other orifices, 6, 7, are also made in tube B, and corresponding ones in sleeve I, to allow the exit of water alternately from chambers 2 and 3 into the space beneath diaphragm D, and thence down pipe E, for the supply of the boiler. (See figs. 1 and 4.)

P is a cross-bar or frame, secured to the boiler for the purpose of receiving adjusting-screws Q Q', the object of which is to control at will the distance that the reservoir G may descend in its oscillations.

Instead of constructing the reservoir in two compartments, as above described, it may be formed with but one compartment, or water-chamber, but in such case, in order to allow its proper action, this chamber would be placed on one side of the centre of its motion or oscillation, and its other arm would be weighted sufficiently to act as a counterpoise. When the chamber is empty, the weight of the arm should be sufficient to overcome the weight of the chamber, and also the friction created by the pressure of spiral spring K. When the chamber is filled to a determined degree, it must be then heavy enough to overcome the weight

and spring, and cause the chamber to descend. The action would thus be similar to that of the reservoir with two compartments, but it would not be as desirable a construction, for the reason that it would not afford so constant a supply of water into the boiler.

The operation of my apparatus is as follows:

Water from any source of supply higher than the reservoir G being admitted into tube B, and (reservoir G being in the position shown in black lines in fig. 2) finding no outlet except through orifice 1, it enters pipe N, and so fills chamber 2, until the weight of the water overcomes the pressure of spring K and the weight of the other chamber. This tilting of the reservoir closes the inlet-hole 1, by which chamber 2 was just supplied, and opens two others, namely, the inlet-orifice of pipe N', which is thus brought into coincidence with orifice 1, (see red lines in fig. 2,) and so admits water into chamber 3, and the steam-inlet 4, by which steam from the boiler is admitted into the water-charged chamber 2 at the same time an outlet is opened for the discharge of the water from chamber 2, through orifice 6, into pipe E, to supply the boiler. The converse of this action takes place when chamber 3 has become filled enough to cause it to descend, steam from the boiler being admitted through pipe O and orifice 4 whenever the water-charged chamber 2 of the tank or reservoir occupies the position shown in figs. 3 and 4, and the steam being admitted through pipe O' and orifice 5 whenever the water-charged chamber 3 occupies the position shown in black lines in fig. 2. The effect of this inward flow of steam into the tank-chamber simultaneously with the flowing out therefrom and into the boiler of the water with which it is charged, is that it equalizes the pressure of the steam upon the water, both above it and below it, the steam which is flowing into the tank overcoming and neutralizing the resistance which would otherwise be offered by the steam within the boiler against the entrance of water therein.

It will thus be perceived that an immense saving results from my apparatus, inasmuch as no independent power or engine is required to force water into the boiler against the pressure of the steam, the leading principle of my invention being that the steam itself shall, under the varying conditions of feeding, be so applied on one side of each charge of water, whether large or small, as to meet and reduce practically to zero the pressure of the steam on the other side of the water, thus holding it, in fact, in *equilibrio*.

When it is considered that above ten-horse power is usually needed to force water into a boiler against the pressure of steam at one hundred and thirty pounds to

the square inch, the value of an apparatus which will feed properly a boiler without any power whatever, beyond the mere pressure in any supply-pipe, can hardly be overestimated.

In order to adjust and determine the rapidity with which the water shall flow into the boiler, I make use of the adjusting-screws Q, which limit the descent of either arm of the tank in its oscillations, and thereby permit the inflowing and outflowing orifices to be opened entirely, as when the arms descend to their lowest points, or allows them to be partially opened only, as when the screws restrict to the degree desired the downward movement of the tank. In this way the supply is readily graduated to meet the capacity and the wants of the boiler, for when the descent is greatest, the orifices being fully open, they feed the faster.

In order to control the quantity of water which shall be supplied to the boiler at a single injection, the adjustable pressure-spring K is brought into requisition. When the pressure is great, the tank cannot descend until the weight of water flowing into its chamber is sufficient to overcome the spring-pressure, whatever may be the degree of that pressure. If the pressure be great, the action will be slow, and *vice versa*. By this means we can measure the supply in accordance with the size of the boiler or amount of fire-surface, and may supply as little as possible, provided it be sufficient.

Claims.

1. The combination of the main supply-tube, and its inlet and outlet-orifices, with the oscillating reservoir, and its inlet and outlet-water orifices and steam-orifices, the parts being constructed substantially as shown and described.
2. The combination, with the oscillating reservoir and its water-supply tube, of the plug and diaphragm C D, substantially as set forth.
3. The combination, with an oscillating water-tank, of inlet and outlet-water orifices, or passages, and a provision for graduating, at will, the degree of downward swing of the tank, to vary the rapidity of the supply of water to the boiler, substantially as described.
4. The combination, with the supply-tank, of the adjustable pressure-spring, to graduate at will the quantity of water desired for a single injection.
5. The combination of the adjusting-screws Q with the tilting-tank, substantially as set forth.
